RACK SYSTEM FOR AUTOMATIC DISHWASHER
 Wesley S. Pattison and Joubert Lindstrom, both of Louisville, Ky., assignors to General Electric Company, a corporation of New York

Filed Mar. 26, 1965, Ser. No. 442,905
 6 Claims. (Cl. 312—269)

This invention relates generally to a rack system for an automatic dishwasher, and, more particularly, to a rack system for a top-opening dishwasher.

Two long-standing problems which have heretofore limited the appeal of a top-opening dishwasher are, on the one hand, difficulty of access to the lower dish-supporting rack and, on the other hand, limited capacity of the upper dish-supporting rack due to the opening normally provided therein for access to the lower rack. Various solutions have been proposed for each of these problems; however, it has been discovered that a partial solution to one of the problems usually compounds the other problem. That is, any attempt to increase the capacity of the upper rack in a top-opening dishwasher usually results in less accessibility to the lower rack and, similarly, any attempt to increase accessibility to the lower rack usually results in a loss of capacity to the upper rack. The most successful attempt heretofore to overcome both problems simultaneously is that described and claimed by L. W. Guth in U.S. Patent 3,087,769, issued on Apr. 30, 1963, and assigned to the General Electric Company, assignee of the present invention. The rack system described by L. W. Guth provides only a partial solution to the above discussed problems since there still is some difficulty encountered in placing dishes in the rear portion of the lower rack due to the positioning of the rear section of the upper rack. Accordingly, it would be desirable to provide an improved rack system which facilitates the loading and removal of dishes at the rear portion of the lower rack in a top-opening dishwasher without sacrificing capacity of the upper rack.

Although the rack system described by L. W. Guth in his aforementioned patent enhances the accessibility to the lower rack, it is still necessary with his arrangement to reach well down into the dishwasher cabinet in order to remove and insert dishes into the lower rack. It is inconvenient, especially for women who are shorter than the average, to reach the required distance into the machine. Accordingly, it would be desirable to provide an improved rack system which obviates a long reach down into the dishwasher in order to insert or remove dishes from the lower rack.

It is an object of this invention to provide a rack system for a top-opening dishwasher which increases the accessibility of the lower rack while maintaining or increasing the capacity of the upper rack.

It is also an object of this invention to provide a rack system for a top-opening dishwasher which shortens the distance into the machine which the operator must reach in order to insert or remove dishes from the lower rack.

Briefly stated, in accordance with one aspect of the invention, an improved rack system is provided for an automatic dishwasher and comprises a cabinet having a rear, a front and two side walls with the front wall terminating a substantial distance below the two side walls. A closure member is pivotally secured to the rear wall for movement between a generally horizontal closed position and a generally vertical open position and comprises the top wall of the cabinet. The closure member and the walls define therein a wash chamber. An upper rack is positioned within the upper portion of the wash chamber when the closure member is closed. The upper rack is of such size to consume substantially all the horizontal cross sectional area of the wash chamber when it is positioned therein.

2

Means interconnect the upper rack with the closure whereby the rack moves out of the wash chamber when the closure member is opened. A pivotal link interconnects the rack and the cabinet whereby the rack moves out of the wash chamber in an arcuate path between the side walls and immediately above the upper extremity of the front wall.

With the aforementioned arrangement, as the closure member is opened, the upper rack, which in a conventional top-opening dishwasher arrangement is disposed directly between the access opening and the lower rack, is moved up and out of the wash chamber to enhance the accessibility to both the upper rack and the lower rack. Also, due to the configuration of the cabinet with its short front wall, accessibility to the lower rack is additionally enhanced since it is unnecessary to reach from above the uppermost point of the cabinet down into the wash chamber to insert or remove articles from the lower rack.

In a specific embodiment of the present invention, the lower rack is mechanically linked to the upper rack whereby the lower rack is moved upwardly within the wash chamber as the upper rack is moved out of the wash chamber upon movement of the closure member.

While the specification concludes with claims particularly pointing out and distinctly claiming the subject matter which is regarded as the invention, it is believed the invention will be better understood from the following description taken in connection with the accompanying drawings, in which:

FIGURE 1 is a side elevational view, partially cut away to show details, of an automatic dishwasher utilizing the present invention;

FIGURE 2 is a partial front elevational view, partially cut away to show details, of the automatic dishwasher illustrated in FIGURE 1; and

FIGURE 3 is a fragmentary side view similar to that of FIGURE 1 but showing the closure member of the dishwasher in the open position.

Referring now to the drawings, and particularly to FIGURE 1 thereof, there is illustrated a top-opening portable dishwasher 10. Dishwasher 10 includes an outer cabinet having a rear wall 11, a front wall 12, and a pair of oppositely disposed side walls 13. The aforementioned walls define therein a wash chamber 14. The cabinet has an open top which serves as an access opening for the admission of articles to, and removal of articles from, wash chamber 14. This access opening is provided with a closure member 15 pivotally secured to rear wall 11 by a hinge means 16. Closure member 15 comprises the top wall of the cabinet to further define wash chamber 14. Hinge means 16 may include suitable counterbalance means to compensate for the weight of closure member 15 and the weight of other elements, to be discussed more fully hereinafter, which are carried by closure member 15.

The lower extremity of wash chamber 14 is defined by a bottom wall 19, the periphery of which is in liquid-tight relationship to the walls 11, 12, and 13. Bottom wall 19 has a centrally depressed portion forming a sump 20 in which liquid will collect. Disposed within sump 20 and supported by bottom wall 19 is a motor-pump assembly 21 which includes an electrically-reversible drive motor 22 and a pump 23. Mounted for rotation at the top of pump 23 is a reaction-type spray arm 24. Pump 23 has an inlet 25 extending substantially around the entire lower periphery of pump 23 and through which wash fluid enters from sump 20. Pump 23 is of the type which, during rotation of motor 22 in one direction, withdraws wash fluid from sump 20 through inlet 25 and propels it upwardly into spray arm 24 to effectuate a washing action within chamber 14. During the opposite direction of rotation of motor 22, pump 23 withdraws wash fluid from sump 20 through inlet 25 and propels it out through a

discharge means (not shown) communicating with a household sewer system. An electrical resistance heating element 26 is supported by bottom wall 19 and is provided to facilitate drying of articles within wash chamber 14 upon completion of washing and rinsing operations.

Of course, means must be provided within wash chamber 14 to support articles or dishes to be washed in a manner whereby the wash action generated by the spray arm 24 effectuates cleansing of the articles. This means usually includes a lower dish-supporting rack and an upper dish-supporting rack. As discussed above, top-opening dishwashers of the type illustrated in FIGURE 1 have faced a two-fold problem of providing suitable accessibility to the lower rack while at the same time maintaining maximum capacity of the upper rack. Prior to the introduction of the arrangement described and claimed in the above-mentioned U.S. Patent 3,087,769, the conventional means for access to the lower rack comprised a large central opening in the upper rack through which articles could be passed to place them in, or remove them from, the lower rack. The arrangement set forth in U.S. Patent 3,087,769 made a significant contribution in overcoming the above-described two-fold problem; however, with such an arrangement there still existed some inconvenience in inserting and removing articles from the lower rack due to the fact that it was permanently positioned near the bottom of the wash chamber which necessitated the operator of the dishwasher to reach through the top access opening and well down into the wash chamber.

In accordance with the present invention, an improved rack system is provided and includes an upper rack 27 and a lower rack 28, each of which consume substantially all of the horizontal cross-sectional area of the wash chamber 14 at their respective levels. Rack 28 is provided with a plurality of supports 29 which normally rest upon bottom wall 19 to support rack 28 in the position shown in FIGURE 1 when closure member 15 is closed. Means are provided to interconnect upper rack 27 with closure member 15 and these means include a generally V-shaped bracket 30 rigidly secured to closure member 15 and extending into wash chamber 14 when closure member 15 is closed and a cooperating bracket 31 rigidly secured to rack 27 and coupled with bracket 30. Brackets 30 and 31 are coupled together in such a manner that when bracket 30 moves during opening of closure member 15, it engages bracket 31 in a manner best shown in FIGURE 3 to lift bracket 31 and rack 27 up and out of the wash chamber 14 as closure member 15 is opened fully to the position shown in FIGURE 3. In the preferred form of the present invention, a second V-shaped bracket 32 and a second cooperating bracket 33 are provided at the opposite side of rack 27 to render rack 27 more stable during its movement out of, or into, wash chamber 14. An extension 34 depends from rack 27 and is provided with means to pivotally connect with a link 35 which, at its other end, is pivotally connected to a cabinet side wall. Link 35 serves to control the amount of tipping, or angular departure from the horizontal, of rack 27 as rack 27 moves up and out of wash chamber 14. With the aforementioned arrangement, a substantial parallelogram is established with link 35 serving as one leg, rack 27 and extension 34 as the second leg, bracket 30 and closure member 15 as the third leg, and cabinet 11 as the fourth leg. It is to be understood, of course, that a precise parallelogram is not required and the degree of departure from a true parallelogram is governed by the degree of tipping of rack 27 which may be desired.

It should be noted that brackets 30 and 31, as well as brackets 32 and 33, are loosely coupled together when closure member 15 is closed. The apex of bracket 30 contacts bracket 31 only after closure member 15 has pivoted approximately 13° whereupon movement of bracket 31 and rack 27 begins. The present arrangement thereby provides a lost motion mechanism between closure mem-

ber 15 and rack 27. It is to be understood, of course, that brackets 30 and 31 may be arranged to vary their relationship whereby closure member 15 pivots through some angle other than approximately 13° before rack 27 begins its movement. The delay in movement of rack 27 relative to the movement of closure member 15, as provided by the lost motion mechanism, serves the significant purpose of allowing closure member 15 to move out of the path of rack 27 since rack 27 has initial forward movement as well as vertical movement. This arrangement, of course, makes feasible the use of a rack 27 which consumes substantially all of the horizontal cross-sectional area of wash chamber 14 when positioned therein.

The configuration of closure member 15 and the cabinet walls is such that a substantially rectilinear wash chamber 14 is provided even though front wall 12 of the cabinet terminates at a level below the side walls and the rear wall. This is achieved by a depending front wall portion 36 and depending side wall portions 37 and 38 of closure member 15. The top edge of the cabinet walls is provided with a sealing means 39 suitably secured thereto. The sealing means 39 provides a liquid-tight seal between closure member 15 and the upper edges of the cabinet wall. Of course, suitable latching means may be provided, although not shown, to secure closure member 15 in liquid sealing relationship with sealing means 39.

By having front wall 12 terminate at a level below the rear wall and side walls, certain advantages are obtained. For example, it is possible to make rack 27 of a size wherein it consumes substantially the entire horizontal cross-sectional area of wash chamber 14 without encountering any interference with cabinet walls as it moves up and out of wash chamber 14 during opening of closure member 15. By shortening front wall 12, it is possible to support rack 27 so that it follows an arcuate path which carries it forward over the top of front wall 12. Also, once rack 27 assumes the position shown in FIGURE 3, the short front wall 12 provides much easier access to lower rack 28 even if rack 28 were to remain in the position shown in FIGURE 1 at the bottom of wash chamber 14.

In order to stabilize rack 27 and prevent it from tipping when it is in the position illustrated in FIGURE 1, during which time brackets 30 and 32 are only loosely coupled with brackets 31 and 33 respectively, a stop 40 projects inwardly from wall 11 to contact rack 27. Also, a stop similar to stop 40 may be provided to project inwardly from one or both of the side walls adjacent the front wall 12 to contact the front portion of rack 27 to provide further stabilization for rack 27; however, in the preferred form of the invention further apparatus, to be more fully discussed hereinafter, provides the necessary stabilization of rack 27 so that the second stop is obviated.

Although the arrangement as thus far described provides an improved rack system which greatly enhances the accessibility to the lower rack of a top-opening dishwasher, by moving the upper rack out of the wash chamber, while at the same time sacrificing no capacity of the upper rack, a specific embodiment of the present invention provides means to further enhance accessibility of the lower rack by moving the lower rack upwardly within wash chamber 14 as closure member 15 is opened. This means includes a stationary member or guide 41 having an elongated slot 42. Slot 42 receives a pair of rollers 43 and 44 which are rotatably secured to a plate 45. Due to the relationship between rollers 43 and 44 and slot 42, plate 45 is free to move up and down and its direction of travel is guided by slot 42. Plate 45 is rigidly secured to lower rack 28 so that rack 28 moves with plate 45. Rollers 43 and 44 are each spaced a short distance from plate 45 and disposed within this space are smaller rollers or sleeves 46 and 47 respectively. Sleeves 46 and 47 are carried by the same pins which carry rollers 43 and 44 respectively. A second link 48 is pivotally secured

to extension 34 at the same point that link 35 is secured thereto. Link 48 may actually take the form of a piece of rod or tubing bent into an elongated closed loop thereby providing, in effect, a link having therein a slot extending for substantially the entire length of the link. Link 48 is coupled with sleeve 46 so that, as closure member 15 and rack 27 have moved upwardly partially, i.e., when closure member 15 has pivoted about 45°, the lower extremity of link 48 contacts sleeve 46 to pull plate 45 upwardly therewith. As the movement of all of the elements continues, the entire system will eventually assume the relationship illustrated in FIGURE 3 when closure member 15 reaches its full open position. In this position, rack 28 is at substantially the same level as the top of front wall 12.

Plate 45 is purposely elongated so that rollers 43 and 44 may be spaced from each other a substantial distance to provide the desired stability of lower rack 28 during its movement upwardly and during the time that it is in the position illustrated in FIGURE 3. It is to be understood that a second stationary member similar to member 41, and all of the associated elements including the rollers, plate, sleeves and link may be provided at the opposite side of the rack 28, if desired, to further increase the stability of rack 28.

A second stop 49, best seen in FIGURE 3, is associated with link 48 to contact sleeve 46 when the system assumes the position illustrated in FIGURE 1 to limit the downward movement of rack 27 and to cooperate with stop 40 to stabilize rack 27 when it is in the position illustrated in FIGURE 1.

Thus it can be seen that the afore-described arrangement provides an improved rack system for a top-opening dishwasher which increases the accessibility of the lower rack while maintaining or increasing the capacity of the upper rack. In a specific embodiment of the present invention, the access to the lower rack is additionally enhanced due to the upward movement thereof to avoid the necessity for the operator to reach down into the wash chamber to insert or remove dishes from the lower rack.

As will be evident from the foregoing description, certain aspects of the invention are not limited to the particular details of construction of the example illustrated, and it is contemplated that various other modifications or applications will occur to those skilled in the art. It is therefore intended that the appended claims shall cover such modifications and applications as do not depart from the true spirit and scope of the invention.

What we claim as new and desire to secure by Letters Patent of the United States is:

1. An automatic dishwasher comprising:

(a) a cabinet having a rear, a front and two side walls,

(b) said front wall terminating a substantial distance below said side walls,

(c) a closure member comprising the top wall of said cabinet and being pivotally secured to said rear wall for pivotal movement between a closed position and an open position,

(d) said closure member and said walls defining a wash chamber,

(e) an upper rack positioned within the upper portion of said wash chamber when said closure member is closed,

(f) said upper rack consuming substantially all the horizontal cross-sectional area of said wash chamber when positioned therein,

(g) means interconnecting said upper rack and said closure member whereby the entire rack moves out of the wash chamber when said closure member is opened, and

(h) a pivotal link interconnecting said rack and said cabinet whereby said rack moves out of said wash chamber in an arcuate path between said side walls and immediately above the upper extremity of said front wall.

2. An automatic dishwasher comprising:

(a) a cabinet having a rear, a front and two side walls, (b) said front wall terminating a substantial distance below said side walls,

(c) a closure member comprising the top wall of said cabinet and being pivotally secured to said rear wall for pivotal movement between a closed position and an open position,

(d) said closure member and said walls defining a wash chamber,

(e) an upper rack positioned within the upper portion of said wash chamber when said closure member is closed,

(f) said upper rack consuming substantially all the horizontal cross-sectional area of said wash chamber when positioned therein, and

(g) means interconnecting said upper rack and said closure member whereby the entire rack moves out of the wash chamber when said closure member is opened,

(h) said means interconnecting said upper rack and said closure member including a lost motion mechanism whereby said closure member pivots partially toward said open position before said upper rack begins to move.

3. An automatic dishwasher comprising:

(a) a cabinet having a rear, a front and two side walls, (b) said front wall terminating a substantial distance below said side walls,

(c) a closure member comprising the top wall of said cabinet and being pivotally secured to said rear wall for pivotal movement between a closed position and an open position,

(d) said closure member and said walls defining a wash chamber,

(e) an upper rack positioned within the upper portion of said wash chamber when said closure member is closed,

(f) said upper rack consuming substantially all the horizontal cross-sectional area of said wash chamber when positioned therein,

(g) means interconnecting said upper rack and said closure member whereby the entire rack moves out of the wash chamber when said closure member is opened,

(h) said means interconnecting said upper rack and said closure member including a lost motion mechanism whereby said closure member pivots partially toward said open position before said upper rack begins to move, and

(i) a pivotal link interconnecting said rack and said cabinet whereby said rack moves out of said wash chamber in an arcuate path between said side walls and immediately above the upper extremity of said front wall.

4. An automatic dishwasher comprising:

(a) a cabinet having a rear, a front and two side walls, (b) said front wall terminating a substantial distance below said side walls,

(c) a closure member comprising the top wall of said cabinet and being pivotally secured to said rear wall for pivotal movement between a closed position and an open position,

(d) said closure member and said walls defining a wash chamber,

(e) an upper rack positioned within the upper portion of said wash chamber when said closure member is closed,

(f) said upper rack consuming substantially all the horizontal cross-sectional area of said wash chamber when positioned therein,

(g) means interconnecting said upper rack and said closure member whereby the entire rack moves out of the wash chamber when said closure member is opened,

- (h) said means interconnecting said upper rack and said closure member including a lost motion mechanism whereby said closure member pivots partially toward said open positions before said upper rack begins to move,
  - (i) a lower rack positioned within the lower portion of said wash chamber when said closure member is closed, and
  - (j) means interconnecting said upper rack and said lower rack whereby said lower rack is moved upwardly within said wash chamber as said closure member is opened.
- 5
5. An automatic dishwasher comprising:
- (a) a cabinet having a rear, a front and two side walls,
  - (b) said front wall terminating a substantial distance below said side walls,
  - (c) a closure member comprising the top wall of said cabinet and being pivotally secured to said rear wall for pivotal movement between a closed position and an open position,
  - (d) said closure member and said walls defining a wash chamber,
  - (e) an upper rack positioned within the upper portion of said wash chamber when said closure member is closed,
  - (f) said upper rack consuming substantially all the horizontal cross-sectional area of said wash chamber when positioned therein,
  - (g) means interconnecting said upper rack and said closure member whereby the entire rack moves out of the wash chamber when said closure member is opened,
  - (h) said means interconnecting said upper rack and said closure member including a lost motion mechanism whereby said closure member pivots partially toward said open position before said upper rack begins to move,
  - (i) a lower rack positioned within the lower portion of said wash chamber when said closure member is closed, and
  - (j) means interconnecting said upper rack and said lower rack whereby said lower rack is moved upwardly within said wash chamber as said closure member is opened,
  - (k) said means interconnecting said upper rack and said lower rack including a lost motion mechanism whereby said upper rack moves partially toward its position out of the wash chamber before said lower rack begins to move.
- 10
- 20
- 25
- 30
- 35
- 40
- 45

6. An automatic dishwasher comprising:
- (a) a cabinet having a rear, a front and two side walls,
  - (b) said front wall terminating a substantial distance below said side walls,
  - (c) a closure member comprising the top wall of said cabinet and being pivotally secured to said rear wall for pivotal movement between a closed position and an open position,
  - (d) said closure member and said walls defining a wash chamber,
  - (e) an upper rack positioned within the upper portion of said wash chamber when said closure member is closed,
  - (f) said upper rack consuming substantially all the horizontal cross-sectional area of said wash chamber when positioned therein,
  - (g) means interconnecting said upper rack and said closure member whereby the entire rack moves out of the wash chamber when said closure member is opened,
  - (h) a pivotal link interconnecting said upper rack and said cabinet whereby said rack moves out of said wash chamber in an arcuate path between said side walls and immediately above the upper extremity of said front wall,
  - (i) guide means carried by said side walls and having a generally vertical elongated slot therein,
  - (j) a lower rack positioned within the lower portion of said wash chamber when said closure member is closed,
  - (k) at least one pair of spaced rollers carried by said lower rack and received by said slot, and
  - (l) means interconnecting said upper rack and said lower rack whereby said lower rack is moved upwardly within said wash chamber as said upper rack moves out of said wash chamber,
  - (m) movement of said lower rack being guided by said guide means and said rollers.
